TREATMENT OF PETROLEUM MATERIALS

Filed Sept. 24, 1931

UNITED STATES PATENT OFFICE

JOHN D. FIELDS, OF LOS ANGELES, CALIFORNIA

TREATMENT OF PETROLEUM MATERIALS

Application filed September 24, 1931, Serial No. 564,944, and in Canada, Venezuela, and Mexico after
August 1, 1931.

This invention relates to a method of refining hydrocarbons and particularly pertains to the treatment of any kind of petroleum oil, either crude or distillates or topped oil or 5 distillation residues or cracking residues, to produce various products therefrom. The oil may be of paraffin base or asphalt base or mixed base and may contain sulfur or not. The residues referred to may be freely liquid 10 or nearly solid or may contain greater or smaller proportions of constituents of a petro-rolatum-like consistency at ordinary atmospheric temperature. The starting material also may be a mixture of two or more 15 of the above mentioned materials, but should contain some fractions less volatile than ordinary kerosene (say 40° Bé.). The material to be treated will hereinafter be termed "petroleum" which term is to be understood in 20 the broad sense here referred to.

The primary object of the invention is to provide a process whereby any petroleum may be treated to produce any one or more 25 of a number of the products of distillation or cracking at the will of the operator from any petroleum available for treatment, and at the same time to effect the production of a hard, dry, commercial coke from the residuum, and also to effect the removal and 30 recovery of resinous and other gummy constituents which if left in the product, would result in discoloration of the distillates and the imparting of objectionable odors thereto. The entire process is carried out in a single 35 apparatus, as illustrated in the annexed drawing.

Another object of the invention is to provide a method whereby petroleum of any boiling point range, may be distilled to effect its 40 conversion into any desired low boiling fractions and coke, whereby a high percentage of low boiling fractions of the hydrocarbon may be obtained and whereby the coke residue formed will be of such a character as 45 to enable its ready removal from the distilling apparatus and also have properties imparted thereto which will render it valuable as a carbon or coke product suitable for use in metallurgical and other operations.

50 Another object of the invention is to pro-

vide a method for purifying the distillates to effect the production of a sweet smelling, water white, absolutely stable distillate product of great brilliancy, and whereby resinous compounds and other gummy im- 55 purities, sulfur compounds and other im- purities, held in solution in the distillates may be removed in a usable condition, without destroying the benzol equivalent and octane number constituents of the distillate, 60 whereby these latter constituents are con- served so as to produce a high grade product which when used as fuel in an internal combustion engine, will not form gummy or resinous deposits. 65

Another object of the invention is the pro- 70 vision of a method whereby the distillates may be refined without material loss thereof thus enabling the production of a greater volume of the purified product from a given volume of distillates under treatment than is obtained by the refining processes hereto- 75 fore used.

A highly important feature of the purify- 80 ing operation resides in dispensing with the use of reactive agents, such as sulfuric acid, alkalis, filtering media and other substances which are lost in the usual treatment of distillates by the acid and alkali treating processes, thereby obviating the expense in- 85 cident to the use of such substances and thus resulting in a process for refining distillates which is of great economic value.

The invention resides generally in distill- 90 ing any petroleum hydrocarbon together with a vegetable substance, with or without the addition of iron ore according to the character of coke product desired, effecting such distillation, with any predetermined amount of cracking, all at predetermined 95 temperatures and pressures, according to the fractions desired thereby producing oil vapors, condensing such vapors, and finally treating the condensed distillates to remove and recover resinous and other impuri- 100 ties therefrom; the invention further re- siding in effecting the last named step by subjecting the impurities in the condensates to the action of a catalytic agent of a charac- ter such that it will act on the impurities and

cause same to separate from the distillate while the latter still retains the benzol and octane number components of the distillates in a manner which will permit ready removal of the impurities. This result is also accomplished without using up the catalytic agent, whereby a given amount of the catalytic agent will theoretically purify an unlimited amount of the distillate, and practically it will purify an immense volume of the distillate. This is because there is substantially no chemical action of the impurities or the oil, upon the catalytic agent, namely alkali metal.

15 The invention and the mode of accomplishing the objects and advantages as may subsequently appear, further resides in the steps and features hereinafter more fully described and claimed and illustrated by way 20 of example in the accompanying drawing in which the figure is a diagrammatic view of a refining apparatus embodying associated instrumentalities employed in producing the results sought.

25 In referring to the drawing A indicates generally a still for initially distilling the petroleum to form distillates and coke, and which embodies a tank or boiler 3 arranged over a fire box 4 in which heat is generated, 30 as by an oil or gas burner 5 or in any other manner. The tank is fitted at its ends with normally closed man-holes 6 and 7 for clean out purposes and through which coke residue is removed, and is fitted with one or 35 more domes or towers 8 connecting to a vapor discharge conduit 9 leading to a condenser B preferably operated under pressure. A low pressure condenser B' is preferably also provided. A pressure gauge 10 is provided on 40 the tank and a pressure relief valve 11 is provided in the conduit 9, which pressure relief valve is adjustable to regulate the pressure in the still. A temperature indicator 12 is mounted on the conduit 9 between the still 45 and the pressure relief valve and preferably near the latter to indicate the temperature of vapors within the conduit. A feed pipe 14 leads to the tank from an oil storage reservoir C or other suitable source of petroleum 50 supply, through which the materials to be treated are directed to the still to charge the latter as occasion requires, and connecting with the feed pipe 14 is a conduit 15 leading from a mixer 16 to which comminuted vegetable matter is delivered from a hopper D with or without finely comminuted iron ore fed to the mixer 16 from a hopper E; the feed of materials from the hoppers D and E being controlled by valves or gates 17 and 18. 55 The feed pipes 14 and 15 are fitted respectively with cut-off valve 19 and a valve or gate 20.

60 The apparatus as shown in the drawing also embodies a series of catalyzer containing tanks F, G and H within which are mounted

perforated catalyzer supports 22, 23 and 24 which are spaced from the bottoms of the tanks and are here shown as composed of wire netting. The spaces 25, 26 and 27 above the supports 22, 23 and 24 constitute catalyzing chambers within which are contained catalytic bodies I, J, and K carried on the supports, which bodies are formed of solid alkali metal, such as sodium, potassium, lithium or mixtures thereof. Metallic sodium is preferred.

65 The catalytic bodies are so shaped and so arranged within the catalyzing chambers as to permit the flow of distillates through said chambers yet cause the flowing distillates to be deflected into numerous small streams which flow through the interstices between adjacent catalytic bodies in such manner that by the time a volume of distillate has passed through a catalyzing chamber the major portion thereof will have been brought into superficial contact with or in close proximity to a considerable area of the surfaces of the catalytic bodies. For this purpose the 70 catalyzers may be shaped in the form of spheres, blocks or bars. They are placed within the tanks as by introducing them through man-holes with which the latter are equipped and which are normally closed by covers, as indicated at 28, 29 and 30. Any 75 water carried by the distillate, being heavier than the distillate will settle out in the bottom of the space 31 below the grid 22 which supports the catalyzer in the first treating tank F.

80 The spaces 31, 32 and 33 beneath the catalyzer supports 22, 23 and 24 constitute settling chambers in which coagulated or other separable foreign contents of the distillates are collected and these may be drawn off from time to time through drain-cocks 34, 35 and 36 fitted in drain pipes 37, 38 and 39 leading from the bottom portions of the tanks to suitable points of discharge. The tanks are fitted with depending tubular baffles 40, 41 and 42 which lead downwardly from the upper ends of the tanks through the catalyzer supports and open to the settling chambers beneath the supports in spaced relation to the lower ends of the tanks.

85 A conduit 44 leads from the liquid discharge end of the condenser B into the upper end portion of the baffle 40 in tank F; a conduit 45 leads from the upper end portion of tank F into the upper end portion of baffle 41 in tank G; a conduit 46 leads from the upper end portion of tank G to the upper end portion of baffle 42 in tank H; and a conduit 47 may lead from the upper end portion of tank H to a finishing still L, or to a filter, as illustrated. The conduits 44, 45, 46 and 47 are each fitted with cut-off valves 48, 49, 50 and 51 respectively, and leading from the conduits 45, 46 and 47 are pipes 52, 53 and 54 leading to a conduit 55 connecting 90

with the discharge side of a pump M. The pipes 52, 53 and 54 are fitted with cut-off valves 56, 57 and 58. The intake side of the pump M connects through a conduit 59 with 5 a tank N containing a mixture of benzene and alcohol, or other suitable reagent for washing the catalyst, after the latter has become so coated as to render such treatment necessary or advisable.

10 Leading from the lower end portions of the tanks F, G and H are pipes 60, 61 and 62 fitted with cut-off valves 64, 65 and 66, which pipes connect with a pipe 67 leading to the upper portion of the tank N. The pump M 15 and its connections affords a means for circulating a cleaning liquid such as a mixture of benzene and alcohol through the tanks F, G and H separately or collectively when effecting cleansing thereof, as will be later described.

A conduit 68 fitted with a cut-off valve 69 leads from conduit 55 to the conduit 47 through which the purifying liquid may be directed from the tank N to the still L.

20 Preferably I provide a battery of stills 3, for example I may employ six of these stills, four being in operation in different stages, a fifth being cleaned out, while a sixth is being recharged. A manifold 71 connects the vapor outlets 9 from the several stills 3. A low pressure condenser 72 may be connected to the pipes 9, through valved by-passes 73, and during a portion of the run, say during the distillation of the last six or eight per cent 25 of the recoverable oil, the vapors may go into this low pressure condenser, and the condensate may be drawn off separately through valved pipe 74, or it may pass through valved pipe 75 into the main condensate line 44.

20 There may also be provided a branch of pipe 44 into a dewatering device, thence into baffle 40.

It is also advisable to have thermometers or thermocouples (pyrometers) at any suitable place in the still, as shown at 84, to show the temperatures in the body of oil mixture.

In carrying out the invention by means of the apparatus here shown, a liquid petroleum is delivered to the still A through the conduit 14 from the reservoir C together with a quantity of ground or comminuted moist vegetable matter, to which vegetable matter is added, and if required, a quantity of finely comminuted iron ore; the iron ore being added 50 where it is desired to produce a ferruginous coke of hard character and being omitted where it is desired to produce a soft, dry coke. Instead of gravity flow, the mixture of oil, vegetable matter and iron ore (if the latter is used) can be pumped into the still, and this mixture is readily pumpable at any temperature at which the oil is liquid.

As is well known there is a difference in the quality and character of the two kinds of coke referred to (hard coke and soft coke),

and that such cokes have distinctive properties which render them suitable for use for different purposes, for example, soft coke is more valuable than a hard coke in the manufacture of carbon articles, and as a fuel in certain types of stoves or furnaces, while the hard coke with an iron content is useful in blast furnaces and metallurgical operations where the use of soft coke is not practical.

The petroleum to be treated may be of any character; the invention, however, being particularly applicable to the treatment of petroleum of either asphalt or paraffin base having a high initial boiling point, for example, of approximately 650 degrees Fahrenheit. Such products are, at present, obtainable at very small cost, being practically unutilizable by the methods heretofore known, except as fuel, and then only when mixed with thinner oils.

The vegetable matter employed is preferably of such character as to be capable of giving, when strongly heated, alcohol, acetic acid, acetone, phenols and terpenes. As examples of such vegetable matter suitable for the purpose, are mentioned, saw dust, kelp, extracted beet pulp, sugar cane bagasse, and other substances of similar nature, but any vegetable matter which is substantially free of proteins, and capable of being converted into charcoal may be used. Vegetable matter in a green or natural state (i. e. containing a considerable percentage of moisture) is preferably employed. When dry vegetable matter is to be used, I preferably wet the same with water, before use.

The iron ore may consist of any ore which is subject to being reduced to metallic iron, and before being added to the other substances is comminuted to such state of pulverization or fineness that when added to said substances will be held in suspension by the vegetable matter. Iron oxide or carbonate ore reduced to a fineness of from 150 to 250 mesh has been found satisfactory. The ore obviously should not contain a high percentage of sulfur.

The vegetable matter, iron ore and hydrocarbon may be combined in various proportions depending on the characteristics of said substances and the nature of the products thereof desired, but the hydrocarbon is employed in sufficient quantity relative to the quantity of the vegetable matter as to form a liquid flowable, pumpable mass, when at a temperature at which the oil is freely liquid. An example of a specific proportion of the substances, found to be satisfactory, is 3 to 10 parts of vegetable matter, 2 to 10 parts of iron ore and 80 to 97 parts of a liquid petroleum hydrocarbon. As stated, the iron ore is sometimes omitted.

The mixture of substances placed in the still is subjected to the combined action of a temperature and pressure sufficient to effect

destructive distillation of the vegetable matter, and thereby drive off alcohols, pyrolytic acid, essential oils and other vaporized constituents from the vegetable matter, to 5 separate any low boiling fractions from the petroleum used, to produce the desired amount of cracking of the oil, and to reduce the residuum to a dry coke. A temperature of from 350 to 650 degrees Fahrenheit (150 10 to 343° C.) has been found highly satisfactory, although higher temperatures up to say 750° F., (400° C.) may be employed as where heavier fractions are to be produced; it being evident that the higher the temperature 15 to which the materials are subjected in the still the greater separation of the heavier fractions from the hydrocarbons under treatment will result.

While a wide range of pressures may be 20 employed in the still during the distilling operation, it has been found in practice that by subjecting the material under treatment to a pressure of approximately 100 pounds with a temperature of approximately 650 degrees 25 Fahrenheit, a maximum of carbon is produced with a maximum of low boiling fractions, although variations of the pressure and temperature are resorted to as occasion may require.

30 The pressures in the still A are indicated by the pressure gauge 10 and the temperatures of the outgoing vapors are shown by the temperature indicator 12. The desired pressure and variations thereof is obtained 35 by adjusting the pressure control valve 11, and the desired temperature and variations thereof is obtained by controlling the heat generated in the fire box 4 as by regulating the burner 5. A reduction of temperature 40 in the still may be effected by feeding additional liquid hydrocarbon with or without additional vegetable matter to the charge contained in the still.

A particularly effective mode of operating 45 the still in treating petroleum already containing a gasoline fraction with its added content of vegetable matter (and optionally iron ore) is to initially heat the contents of the still (without superatmospheric pressure) 50 until the distillate vapors, which pass off through the conduit 9, have a temperature of 400° F., or thereabout; this temperature being maintained for a suitable period to distill off the gasoline content of the hydrocarbon under 55 treatment. The pressure control valve is then set to open at about 100 pounds pressure and the temperature increased to 580 degrees or thereabout to effect conversion of high boiling fractions into low boiling fractions. The temperature is then gradually raised to 650 degrees or thereabout, which 60 temperature is maintained until all high boiling fractions are vaporized, and may be continued until the residuum in the still is dried out, but the temperature may be increased to

say 750 degrees where it is desired to hasten the drying action. At some point after increasing the temperature to 650 degrees or thereabout, that is when the volatiles are sufficiently driven off to the extent of about 90 70 to 95% of the recoverable oil, the pressure control valve 11 or the valve in pipe 73, is adjusted to open under normal atmospheric pressure and is thereafter maintained open 75 so as to relieve the still of internal pressures during the drying out operation, and steam may be blown through the still to hasten this latter result. An important feature of the invention resides in the fact that the distillation of all except the last 6-10% of the recoverable oil may be completed at temperatures not substantially exceeding 650° F., due to the expulsion of the volatile content of the vegetable matter, thus reducing the amount 80 of heat required during distillation under pressure in converting petroleum into gasoline and other distillates.

About 90 to 94% of the recoverable oil in the charge is volatilized and passes from the still, while the liquid and solid matter in the still is at the selected temperature or temperatures between about 580 and 650° F., and while under superatmospheric pressure, leaving in the still only about 6% to 10% of the recoverable oil, together with the charcoal 95 produced from the vegetable matter intimately mixed with the carbon (coke) which has been formed by decomposition of a part of the oil used. The pressure will then begin to drop rapidly, and the relief valve 11 or the valve in pipe 73 is then opened wide. The temperature may then be raised to not over 750° F., driving off at least 5 to 9% of the oil, leaving not substantially over 1% of oil in 100 the coke residue. Hence it is not necessary 105 to use any special coke refining still, such as has generally been used heretofore, for refining petroleum coke.

A thin layer of the woody material being forced into contact with the walls of the still is reduced to charcoal before the formation of any mineral carbon or petroleum coke takes place and this results in the depositing of a very thin layer of the charcoal on the inner surface of the still before any appreciable amount of mineral carbon or coke is formed in the still so that when such mineral carbon or coke is subsequently formed it is largely deposited on the layer of charcoal and accordingly no accumulation of the mineral carbon or coke directly on the metallic walls of the still takes place. Where iron ore is added, the vegetable matter will hold most of the latter in suspension so as to prevent its precipitation to the bottom of the mass during the initial stages of the distilling operation, and the fine ore remains thoroughly admixed with the vegetable matter and hardens the coke as the latter forms near the walls of the still, thus rendering the formed coke highly 110 115 120 125 130

conductive of heat so that it will serve to protect the walls of the still against burning out during the final stages of drying out the coke and also serves to hasten the driving off of the final volatiles from the coke residuum.

5 The coke (which contains iron) also acts as a conductor of heat from the bottom of the still throughout the mass under treatment. However, where the ore is not used, the charcoal will in like manner form a protective coating on the walls of the still, but this does not adhere to the walls of the still as does petroleum coke in the usual coking still and cracking still processes.

10 When the batch under treatment has been subjected to the distillation temperatures as above stated until the desired fractions have been driven off and the charcoal and coke body has been formed, the temperature may

20 then be raised to 750 degrees or thereabout if desired so as to more rapidly drive off the residual oil in vapor form and hasten drying of the coke and charcoal residuum as before stated; the resultant vapors on being con-

25 densed forming a high grade lubricating oil. This higher temperature is rendered possible by the heat-conductive action of the body of charcoal and ferruginous matter in the coke on the walls of the still.

30 In this manner the petroleum distillates are completely removed and the residue of coke dried out. This coke will consist of an admixture of vegetable carbon or charcoal and mineral carbon together with such other

35 solid substances as may result from distillation of the materials under treatment, it including in its composition mineral carbon derived from the petroleum together with charcoal or organic carbon derived from the

40 vegetable matter. If iron ore has been used, the coke will be ferruginous.

After the drying out stage has been effected, the carbon or coke body formed in the still is easily removed from the latter

45 requiring only a rough breaking up with bars, rakes or the like, without the need of the workmen getting into the stills with chisels, to scale the walls. The coke can be raked out, through the man-holes 6 and 7, which

50 operation is easily accomplished because the charcoal layer formed on the walls of the still is easily separable therefrom; the charcoal having no tendency to tenaciously adhere to the metallic surface of the still but only to

55 rest thereon. This is highly advantageous as the mineral carbon (coke) resulting from the distillation of petroleum without the use of vegetable matter, as in the common practice heretofore, sticks tenaciously to the

60 heated metal of the still, usually iron, which adhesion of the carbon to the metal renders its removal very difficult and time-consuming. Furthermore the finished coke product ob-

65 tained by my process will contain, in many cases, not to exceed one per cent volatile mat-

ter whereas ordinary cracking still coke contains eight to eleven per cent volatiles, and accordingly the coke product thus obtained will require no further treatment, but is in commercial form as it comes from the still 70 and is in condition for use. Again, the coke product is hard and firm, with practically no fines and is characterized by a high carbon content. When the iron ore is not used, the coke can be produced with an average of 75 ninety-five per cent fixed carbon.

The coke made according to my process is very low in sulphur content, since the vegetable matter with which the petroleum is distilled converts the sulphur originally in the 80 petroleum into compounds which are removed from the coke residue.

The vegetable matter also serves a useful purpose in that it absorbs a portion of the oil, consequently during the distilling action, 85 moisture and volatile constituents from the vegetable matter and the lower boiling hydrocarbons from the petroleum are produced together. Furthermore, the charcoal residuum resulting from the decomposition 90 of a portion of the vegetable matter, in depositing on the bottom of the still insures a greatly desired uniformity of temperature throughout the walls of the still and this effect is further enhanced by the addition of 95 the iron ore.

The still is charged with a batch of the substances (from time to time, in some cases), the materials subjected to the desired temperatures and pressures, and the accumulated 100 coke removed, and the operations repeated as often as desired without the need of manual labor to chisel the petroleum coke from the bottom and side walls of the still.

105 During the distilling operation, the operator by regulating the temperatures and pressures can take off the desired distillates such as gasoline, kerosene, engine distillate or Diesel engine oil, lubricating oil and kindred products in vapor form, which products 110 are delivered to the condenser B and there condensed in the usual manner. By controlling the temperatures and pressures in the still, kerosene or gasoline or other desired distillate or cracked product, may be produced alone, if desired.

115 The condensed distillates contain certain objectionable impurities which fact necessitates refinement of the distillates to effect removal of such impurities.

120 The preferred amounts of the green or wet sawdust, (iron ore, if used) and petroleum, to give best results in any particular case will depend on the character of the petroleum to be used and the proportions desired in the 125 product.

Example 1
(“Parts” are by weight in the examples)

130 For making gasoline of about 63° Bé., from a heavy thick distillation residue from Cali-

fornia petroleum having an initial boiling point of 650° F. This residue would form about 18% of carbon or actual coke, by cracking the same in a coking still. I may use 100 parts of the said oil (fed in at about 200 to 220° F.) mixed with 8 to 10 parts of green sawdust and about 10 parts of iron oxide ore. The still contents would be heated to about 580° F., the pressure in the still kept at about 100 lbs. above atmospheric and the temperature shown at 12 kept at about 300° F., (these factors being controlled by control of the fire at burner 5 and adjustment of pressure valve 11) during the major part 15 of the run, until about 70-73 parts of gasoline have been distilled over, and a mass of ferruginous coky material containing oil carbon and charcoal and containing 6 to 8% of the recoverable oil remains in the still. Thus 20 there then would remain in the still, a thick porous layer composed essentially of about 18 parts of solid coky carbon from the oil, having about 4-5 parts of charcoal and the ferruginous residue from the iron ore all intimately distributed throughout said coky carbon, and carrying about 4-6 parts of thick residual oil. This layer is however quite different from petroleum coke in that it does not rigidly adhere to the walls of the still, and 25 is a very good conductor of heat. By this time the temperature in the still has risen gradually (after the sawdust has been converted into charcoal) to about 650° F. The pressure then will begin to drop, and the 30 valve 11 may then be opened wide, or the valve in pipe 73 opened wide into the low pressure condenser 72, and the last portion of the oil distilled out at about atmospheric pressure, or under a partial vacuum, suction 35 being applied through pipe 74, or steam is blown through the still to aid in carrying off the vapors. The oils coming over during this last or drying out stage may be kept separate, these oils being heavier than water and 40 of excellent lubricating character, and especially suitable for lubricating bearings under water, such as the propeller shafts of vessels. These oils also are preferably purified by 45 treatment with sodium, as herein described, in a separate small unit of apparatus. The main bulk of the distillate from this run passes from condenser B, through pipe 44 into tank F, and will consist very largely of gasoline. 50

Example 2

100 parts of high gravity California crude of about 22° Bé., which does not contain any gasoline fraction was the oil treated, which 55 oil would give 8 to 10% of coke, 4 to 5 parts wet sawdust, 3 to 4 parts iron oxide ore, are used. The sawdust and iron ore are mixed, and the mixing of this with the oil is performed warm or cold, say at not over 150° F. The fire and the outlet valve 11 are so regulated

as to give a rapid rise of pressure in the still, up to about 100 lbs., the temperature at 84 then being about 580° F., and the temperature at 12 being about 400 to 450°. During the main part of the run, the temperature shown at 84 will rise from 580 to 650° F. The product (after purification) will be a mixture of about equal parts of gasoline, kerosene and Diesel engine oil, which can be separated in the still L, into these separate fractions. 70 75

Example 3

The original oil is a relatively light California crude, at about 35° Bé., containing a substantial fraction (around 35%) of gasoline. The material fed to the still may conveniently be 100 parts of such oil, about 5 parts of chopped up air dry kelp and about 3 parts of iron oxide ore. The still is first filled with the mixture, and at about atmospheric pressure, heated to about 350 to 400° F., to distill off first run gasoline. Then more of the same oil is fed into the still to again fill the same, while continuing the distillation of gasoline at about atmospheric pressure. The still may even be filled up a third time and gasoline distilled therefrom at atmospheric pressure. Or the feed of the oil can be continuous, while the temperature is kept at 350-400° F. Then the valve 11 is adjusted to give a still pressure of about 100 lbs., a still temperature of about 580° F. and a temperature at 12 of about 350° F., which conditions are maintained until a mass of coke and charcoal carrying say 35-40% or so of oil remains. During the latter part of this run, after the major part of the volatile matters from the kelp have been distilled off, the still temperature has gradually risen to 650° F., at which temperature it will remain until about 94% of the recoverable oil has distilled off. The pressure can be dropped to about atmospheric and the valve in pipe 73 opened, and the still temperature then raised to about 750° F., to drive off most of the oil, leaving not substantially over 1% of volatile matter in the coke. 100 105 110 115

In this modification of the process we get three distilled products, the first run (or straight run) gasoline, distilled at about atmospheric pressure, a second run of gasoline by cracking process and a third or final cut of lubricating oil during the last part of the run, collected from condenser 72. The coke product left in the still can be sold directly to smelters without further treatment. 120 125

The above examples are merely a few illustrations of details of operation showing the results which can be secured. By properly adjusting the factors governing (a) still temperature (b) still pressure (c) vapor temperature in line 9, (d) amount of vegetable matter, I am enabled to get the bulk of the product at any desired gravity and 130 boiling point range, or to get mixtures of any

desired final fractions, in the proportions desired, these results being secured from any petroleum oil which is available.

A special feature of the process is that the temperatures at different parts of the still 3 are alike, in which point the process differs from all ordinary cracking processes. Thus (a) the temperature of the inner surface of the still bottom, (b) the temperature of the 10 oil in the bottom of the still, adjacent the bottom plates, (c) the temperature in the upper stratum of the oil in the still and (d) the temperature in the vapor above the oil in the still are all the same or at least within 15 two or three degrees of each other. This condition exists as long as the mixture in the still is a freely flowing mass.

While little is definitely known as to the components of distillates of the character 20 above referred to, particularly as to the exact nature of the undesired impurities formed therein, it is generally recognized that the distillates may contain impurities of a resinous and gummy character, or gum-forming 25 constituents, sulfur compounds, nitrogen bases, and acid compounds and perhaps others. It has heretofore been the practice to effect removal of the impurities present 30 in oil distillates generally, by first treating the distillates with sulfuric or other acids, settling and removing acid sludge; then (if desired) water-washing the acid treated distillates to remove the larger part of the acids that remain in the distillates; washing the 35 distillates with an alkali wash embodying caustic soda, sodium carbonate, or sodium plumbite, to further remove impurities and to neutralize acids; then (if desired) passing the distillates through a filter of clay or 40 atomaceous earth, and in some cases, finally redistilling the distillates.

This practice results in a large waste of the distillates under treatment caused in part by 45 evaporation of the lighter fractions during handling thereof and also results in the loss of the removed valuable constituents and/or impurities which by reason of the acid and alkali treatments are removed and rendered unfit for use, and further entails the loss of 50 the acids, alkalies, and filter media employed in the process. Furthermore, the acid acts to destroy a part of the benzol equivalent and octane number components of the distillates, which if preserved in the refined product 55 would render it of higher grade and of superior quality particularly in the case of gasoline to be used as motor fuel as the benzol equivalent and octane number constituents impart to the products greatly desired anti- 60 knock properties.

The distillates, as produced in the main part of my process, while in liquid form are accordingly directed through conduit 44 into the upper end portion of the tubular baffle 40 65 of tank F, and directed downwardly through

the baffle 40 into the lower portion of the tank where water settles out and whence the distillates flow upwardly through the interstices between the catalytic bodies I to discharge through conduit 45 leading from the 70 upper end portion of the tank F.

Water content of the distillates settles out of the distillates and collects in the lower portion of tank F beneath the catalysts I as indicated at O to be drawn off as required 75 through the drain-cock 34, the water level being indicated by a gauge P with which the tank F is equipped. Water can also be removed in a separator inserted in the line 44, if desired. 80

The distillates flowing through conduit 45 are fed into the upper portion of the tubular baffle 41 in tank G and are thence directed through the spaces between the catalysts J in the latter in the manner described with 85 reference to tank F; the distillates then being delivered from tank G through conduit 46 into the tubular baffle 42 in tank H where the distillates are directed through spaces between the catalysts K in said tank in a 90 like manner and passed to discharge through the conduit 47 leading from the upper end of tank H.

In this fashion the distillates are directed 95 through any suitable number of tanks as occasion may require to subject the resinous and gummy or other impurities of the distillates to the action of the catalysts a sufficient length of time to effect coagulation of such impurities into a flocculent form; the duration of time being varied according to the character of the distillates under treatment. 100

In practice it has been found that by maintaining the liquid distillates in juxtaposition with the catalysts for a period of from three 105 to five hours at ordinary atmospheric temperatures of the liquid will give highly satisfactory results.

The coagulated or flocculent impurities resulting from the action of the catalysts collect in part on the catalyst bodies, and a portion of such impurities are suspended in the distillates a major part of which settles in the tanks G and H and are separated from the distillates in these tanks by drawing off 110 through the drain-cocks 35 and 36 from time to time as occasion may require together with such other separable foreign matter as may accumulate in the settling chambers. 115

Such portions of the flocculent impurities as do not settle and remain in suspension in the distillates can readily be removed from the distillates by redistilling the latter in the still L to which the distillates are delivered from the end tank H through the conduit 47, 120 or may, if desired, be recovered by filtration of the treated distillates in a usual manner. 125

While I do not wish to bind myself to any particular theory regarding the action of the alkali metal used in connection with the re- 130

moval of impurities from the hydrocarbon oil, nevertheless it should be stated in the interest of clarity that the alkali metal probably acts to accelerate a condensing and coagulating action of the impurities in the hydrocarbon, some of which impurities adhere to the surface of the alkali metal while other portions thereof are merely flocculated and remain in suspension. In other words, the alkali metal merely hastens an action that would undoubtedly occur if sufficient time were allowed, and hence I have referred to the action of the alkali metal as a catalytic action.

15 There is apparently no chemical action of the impurities of the oil, or the oil itself upon the alkali metal, but the said metal remains as such, although it becomes coated with impurities separated from the oil, these being generally of a gummy nature. When the amount of such precipitated gummy impurities on the sodium has partly filled up the interstices of the mass, the accumulated impurities are removed by giving the sodium 20 (in situ) a wash with a proper solvent such as a mixture of a benzolic liquid with a little alcohol, say 4 to 8 parts of benzol (benzene) and one part of alcohol.

The distillates after having been treated 30 in the tanks are finally filtered or preferably redistilled; the subsequent treatment of the distillates depending on the character of the treated distillates and the results desired. For example, first run gasoline does not ordinarily require redistilling but in some cases 35 may be benefited thereby. Where the treated distillates embrace light and heavy fractions they are fractionally distilled to separate the same into desired fractions such as 40 gasoline, kerosene, engine distillate and Diesel engine oil.

The catalyzing apparatus as here shown is designed for continuous operation, that is, for a continuous run until conditions necessitate a shut down, and is also designed to facilitate a cleaning out operation to effect 45 recovery of the coagulated impurities as will presently be described, but manifestly any suitable catalyzing apparatus may be employed to carry out the process.

In the course of a protracted run of the distillates through the catalyzing chambers the catalyzers will become coated with a gummy resinous mass consisting of the impurities 50 before referred to, which coating while not interfering with the catalytic action must be removed in order to obviate clogging of the catalyzing tanks and also to effect recovery of the substances constituting such 55 coating. This is accomplished by discontinuing flow of the distillates through the catalyzing tanks, draining the fluids from the tanks, then filling the tanks with a solvent of the separated impurities. For this purpose, benzene is used as a solvent to which

is added a quantity of alcohol for the purpose of activating the catalyzers. A volume of alcohol of from three to ten per cent of that of the benzene is ordinarily employed, but any suitable proportion of alcohol may be used as occasion may require. A proportion of one part of absolute denatured alcohol with twenty to twenty-five parts of benzol or its homologues gives very satisfactory results.

70 The solvent is directed through one or more of the catalyzing tanks from the tank N by means of the pump M and the pipes leading therefrom to the catalyzing tanks; the previously closed valves in said pipes being opened 75 and the previously open valves in the several conduits communicating with the catalyzing tanks being closed according to the desired direction of flow of the solvent. For example, on closing the valves 48 and 49 and 80 opening valves 56 and 64 and operating the pump M the solvent will be directed through the tank F, or by closing valves 49 and 50 and opening valves 57 and 65 the solvent will be directed through tank G, or by closing 85 valves 50 and 51 and opening valves 58 and 66 the solvent will be directed through the tank H.

To direct the solvent through the series of tanks the valves 48 and 51 are closed and 90 valves 58 and 64 opened while valves 56, 57, 65 and 66 are maintained closed. When it is desired to redistill the solvent benzene and alcohol, to separate it from the dissolved 95 gummy matters therein, it is directed from the tank N to the still L through conduit 100 68 on opening the valve 69.

The coated catalyzers can be maintained submerged in the benzol-alcohol bath preferably at room temperature, or at a lower temperature, for a sufficient length of time to effect dissolving of the coating of impurities, and the bath is removed from the tanks with the dissolved impurities held in solution 105 therein and is distilled in such manner as to effect separation and recovery of the benzol and alcohol and the previously dissolved substances contained therein.

110 By employing alcohol in the benzol solvent a slight amount of chemical action may take place on the alkali metal bodies. Such action leaves the surface of the metal bright and will hasten the formation of the flocculent gummy resinous matter when the metal is again contacted with the oil distillate the 115 tendency of the gummy matter to cling to the surfaces of the bodies, and also renders the separation of the coating from the bodies more rapid and thorough. It is therefore desirable to also subject the alkali metal 120 bodies to an alcohol containing bath (e. g. this same benzol-alcohol mixture) before initially employing said alkali metal bodies in the treatment of the distillates.

125 After having thus washed the catalyzers 130

with the benzol-alcohol bath and cleansed the tanks of the solvent, the apparatus is thereby conditioned in readiness for another run of the distillates to be treated. This treatment with the solvent bath requires a short period, say 10-15 minutes, and the benzol-alcohol mixture is removed from contact with the alkali metal as soon as the latter is cleaned up, in order to prevent any further action of the alcohol on the alkali metal, which would of course use up and waste the alkali metal.

For observing the alkali metal, glass peep holes or windows may be provided in the walls of the tanks F, G and H.

The removed impurities are of resinous or gummy character and as recovered are in the form of a gum or wax, which substances possess valuable qualities and may be employed in various uses, such for example as an added constituent to fuel oil or road oil, and as a wax for use in the manufacture of candles or it can be worked up into a rubbery material.

An important feature of the invention resides in the fact that the catalytic action effected by the alkali metal can be carried on at normal atmospheric temperatures and at the ordinary temperatures of the liquid distillates (60 to 90° F.) and hence does not require the generation and application of extraneous heat, and also that the entire purification may be carried on at normal atmospheric pressures. Temperatures much above 125° F. should be avoided in this step, otherwise a hard coky coating will form, on the surface of the alkali metal, which coating would be difficult to remove from the surface of the pieces of said alkali metal, and furthermore at any temperatures substantially above 100° F., there appears to be some chemical action of some of the impurities of the oil, on the alkali metal whereby a portion of the latter is consumed. Preferably I treat the oil distillate with the alkali metal as the latter leaves the condenser, when at about 55 to 70° F., but for treating gasoline received in tank cars, oil barges, from pipe lines, etc., the material can be first cooled to 60 to 70° F., if refrigerating equipment is available, or can be treated at any temperature below 100° F.

As is well known, commercial gasoline shows a tendency to form gums and to turn yellow or somewhat brownish in color, in storage, whether exposed to the light or not. Also the odor of the gasoline generally gets bad during storage. Other oil distillates such as petroleum ether, naphtha, kerosene, Diesel engine oil, show this tendency to a greater or less extent. Distillates which have so deteriorated can be treated by flowing through the tanks containing the alkali metal, to be thereby brought back to water white or even to 30° Saybolt color, and are there-

by rendered stable. Dye in the oil so treated is usually also removed by this treatment. This refining here referred to may be applied to gasoline and other distillates made by previously known straight run or cracking processes and purified by the conventional processes, and (if desired) afterwards blended with other gasolines, petroleum distillates, benzol, etc. While purification is thereby accomplished to a wholly satisfactory degree, my catalytic purification process obviously does not add anti-knock constituents which have been removed in any acid treating process to which the distillates have been subjected. Such anti-knock constituents as are well known in the art can of course be subsequently (or even previously) added, when desired.

The crude distillates produced in my process are generally much purer than the crude cracked distillates produced in any of the commonly employed cracking processes with which I am familiar. Thus the first distillate produced in Example 1, may be a pale yellow distillate having a rather sweet odor, even when the original oil contains a substantial percentage of sulphur. It is my belief that some of the products of destructive distillation of the wood sawdust have reacted with the sulphur compounds of the oil in the still A and in the refluxing domes (or towers). This distillate could be purified by treatment with sulphuric acid and soda by the conventional method, requiring less acid than gasoline made by the other well known high temperature cracking processes. However the acid would destroy a substantial amount of the anti-knock constituents of the distillate, hence the sodium treatment is far preferable and produces from this distillate a better refined product than could be produced by any other process known to me.

In the tank C may be provided a steam coil for warming up the oil, especially if the oil is very thick and viscous.

I have above referred to sodium as the most economical of the alkali metals. Also potassium, lithium, calcium, strontium and barium (in the metallic state) could be employed, if desired. These metals I refer to hereinafter as "alkali metal".

I have above referred to sawdust and kelp in the examples. Other kinds of vegetable matter are comminuted corn cobs, peat, other comminuted wood, or woody material, preferably such as do not contain any substantial percentage of sulfur or large amounts of protein. Straw, chaff, comminuted bark (e.g. spent tan) if available, could be used although they might increase the silica content of the coke somewhat.

This application is a continuation in part of my copending application, Serial No. 549,862 filed July 10, 1931.

I claim:—

1. A process of refining a distillate produced by distillation of a mixture of 80 to 95 parts of petroleum hydrocarbons, 3 to 10 parts of solid comminuted vegetable matter rich in carbohydrates, and 2 to 10 parts of comminuted iron ore, whereby at least a part of the hydrocarbons are cracked and vaporized, and condensing the evolved vapors, which process comprises subjecting such condensed distillate to prolonged contact with an alkali metal in a free state, at atmospheric pressure but not above 125° F., until at least some of the impurities in the distillate are coagulated, and separating the coagulated impurities.

2. A process of refining a cracked distillate produced by heating petroleum mixed with a few per cent of its weight of a solid carbonizable vegetable matter consisting largely of carbohydrates, to a temperature capable of causing destructive distillation of said vegetable matter and capable of causing cracking and distillation of said petroleum and condensing the vapors thereby liberated, which process comprises subjecting such condensed distillate in a liquid state to prolonged contact with an alkali metal in the free state, while at atmospheric temperature but below 125° F., until some at least of the impurities in the coagulated impurities from the distillate.

3. A process of refining a cracked distillate produced by heating petroleum mixed with a few percent of its weight of sawdust, to a temperature capable of causing destructive distillation of said sawdust and capable of causing cracking and distillation of said petroleum and condensing the vapors thereby liberated, which process comprises subjecting such condensed distillate in a liquid state to prolonged contact with an alkali metal in the free state, while at atmospheric temperature but below 125° F., until some at least of the impurities in the distillate are coagulated, and separating the coagulated impurities from the distillate.

4. A process of refining a cracked distillate produced by heating petroleum mixed with a few per cent of its weight of kelp, to a temperature capable of causing destructive distillation of said kelp and capable of causing cracking and distillation of said petroleum and condensing the vapors thereby liberated, which process comprises subjecting such condensed distillate in a liquid state to prolonged contact with an alkali metal in the free state, while at atmospheric temperature but below 125° F., until some at least of the impurities in the distillate are coagulated.

5. A process of refining a cracked distillate produced by heating petroleum mixed with a few per cent of its weight of moist solid carbonizable vegetable matter consist-

ing largely of carbohydrates, to a temperature capable of causing destructive distillation of said vegetable matter and capable of causing cracking and distillation of said petroleum and condensing the vapors thereby liberated, which process comprises subjecting such condensed distillate in a liquid state to prolonged contact with an alkali metal in the free state, while at atmospheric temperature but below 125° F., until some at least of the impurities in the distillate are coagulated, and separating the coagulated impurities from the distillate.

6. A process of refining a cracked distillate produced by heating petroleum mixed with a few per cent of its weight of a solid carbonizable vegetable matter consisting largely of carbohydrates, to a temperature not substantially above 650° F., during most of the heating, but sufficient for causing cracking and distillation of said petroleum and condensing the vapors thereby liberated, which process comprises subjecting such condensed distillate in a liquid state to prolonged contact with an alkali metal in the free state, while at atmospheric temperature but below 125° F., until some at least of the impurities in the distillate are coagulated, and separating the coagulated impurities from the distillate.

7. A process of refining a cracked distillate produced by heating petroleum mixed with a few per cent of its weight of a solid carbonizable vegetable matter consisting largely of carbohydrates, to a temperature capable of causing destructive distillation of said vegetable matter and capable of causing cracking and distillation of said petroleum and condensing the vapors thereby liberated, which process comprises subjecting such condensed distillate in a liquid state to prolonged contact with an alkali metal in the free state, while at about 55° to 100° F., until some at least of the impurities in the distillate are coagulated, and separating the coagulated impurities from the distillate.

8. A process of refining a cracked distillate produced by heating petroleum mixed with a few per cent of its weight of a solid carbonizable vegetable matter consisting largely of carbohydrates, while under a superatmospheric pressure of several atmospheres, to a temperature capable of causing destructive distillation of said vegetable matter and capable of causing cracking and distillation of said petroleum and condensing the vapors thereby liberated, which process comprises subjecting such condensed distillate in a liquid state to prolonged contact with an alkali metal in the free state, while at atmospheric temperature but below 125° F., until some at least of the impurities in the distillate are coagulated, and separating the coagulated impurities from the distillate.

9. A process of refining a cracked distillate

produced by heating petroleum mixed with a few per cent of its weight of a solid carbonizable vegetable matter consisting largely of carbohydrates, while under a superatmospheric pressure not substantially exceeding 6 100 lbs., during most of the heating, to a temperature capable of causing destructive distillation of said vegetable matter and capable of causing cracking and distillation of 10 said petroleum and condensing the vapors thereby liberated, which process comprises subjecting such condensed distillate in a liquid state to prolonged contact with an alkali metal in the free state, while at atmospheric 15 temperature but below 125° F., until some at least of the impurities in the distillate are coagulated, and separating the coagulated impurities from the distillate.

10. A process of refining a cracked distillate produced by heating petroleum mixed 20 with a few per cent of its weight of a solid carbonizable vegetable matter consisting largely of carbohydrates, to a temperature capable of causing destructive distillation of said vegetable matter and capable of causing cracking and distillation of said petroleum and condensing the vapors thereby liberated, which process comprises subjecting such condensed distillate in a liquid state and while 25 at substantially atmospheric pressure, to prolonged contact with an alkali metal in the free state, while at atmospheric temperature but below 125° F., until some at least of the impurities in the distillate are coagulated, 30 and separating the coagulated impurities from the distillate.

11. A process of refining a cracked distillate produced by heating petroleum mixed 40 with a few per cent of its weight of a solid carbonizable vegetable matter consisting largely of carbohydrates, and fine iron ore, to a temperature capable of causing destructive distillation of said vegetable matter and capable of causing cracking and distillation 45 of said petroleum and condensing the vapors thereby liberated, which process comprises subjecting such condensed distillate in a liquid state to prolonged contact, with an alkali metal in the free state, while at atmospheric 50 temperature but below 125° F., until some at least of the impurities in the distillate are coagulated, and separating the coagulated impurities from the distillate.

12. A process of refining a cracked distillate produced by heating petroleum mixed 55 with a few per cent of its weight of a solid carbonizable vegetable matter consisting largely of carbohydrates, to a temperature capable of causing destructive distillation of 60 said vegetable matter and capable of causing cracking and distillation of said petroleum and condensing the vapors thereby liberated, which process comprises subjecting such condensed distillate in a liquid state to contact 65 for several hours with an alkali metal in

the free state, while at atmospheric temperature but below 125° F., until some at least of the impurities in the distillate are coagulated, and separating the coagulated impurities from the distillate.

13. A process of refining a distillate produced by cracking and distillation of petroleum mixed with a few per cent of comminuted vegetable carbohydrate matter of the type of wood, kelp, straw, and bagasse, 70 which is of such a size of particle as to be readily suspended in said petroleum, such cracking and distillation being effected at a temperature at which such vegetable carbohydrate matter is destructively distilled, and condensing the evolved vapors, which process comprises contacting such condensed distillate with an alkali metal in a free state, 75 at between about 55 and 125° F., for a substantial period of time and until at least some of the impurities in the distillate are coagulated, and separating the coagulated impurities.

In testimony whereof I affix my signature.
